UNITED STATES PATENT OFFICE.

ELMER W. BISHOP, OF SEDRO WOOLLEY, WASHINGTON.

CAN-OPENER.

No. 913,683.

Specification of Letters Patent.

Patented March 2, 1909.

Application filed November 7, 1908. Serial No. 461,553.

To all whom it may concern:

Be it known that I, ELMER W. BISHOP, a citizen of the United States, residing at Sedro Woolley, in the county of Skagit and State of Washington, have invented certain new and useful Improvements in Can-Openers, of which the following is a specification, reference being had to the accompanying drawings.

10 This invention relates to improvements in can openers and its object is to provide a simple and practical device of this character by means of which a tin can or the like may be quickly and easily opened.

15 With the above and other objects in view, the invention consists of the novel features of construction and the combination and arrangement of parts hereinafter fully described and claimed, and illustrated in the 20 accompanying drawings, in which—

Figure 1 is a perspective view of the improved can opener; Fig. 2 is a side elevation of the same; and Fig. 3 is a plan view of the cutting blade or knife.

25 The invention comprises a suitable support 1 upon which is mounted a lever 2 carrying a cutting blade or knife 3. The support 1 is preferably in the form of an upright post rising from a base board 4 and having the lever 30 2 pivoted to its upper end. Said lever has a suitable handle 5 at its outer end and its inner end 6 is reduced and adjustably pivoted in a vertical slot or opening 7 formed in the upper portion of the upright 1. This adjustable pivotal connection is effected by forming 35 in the slotted portion of the upright a series of transverse alining openings 8 adapted to receive a removable pivot pin 9 which also passes through an opening in the reduced end 40 6 of the lever. By making the pivotal connection of the lever vertically adjustable the device is adapted for operation upon cans of different sizes.

The improved cutting blade or knife 3 is 45 fixed to the intermediate portion of the lever 2 and is adapted to be forced downwardly by the latter and into the top of a can C indicated in dotted lines in Fig. 2. Said knife 3 is of substantially circular shape but open 50 at its rear side, as shown at 10, and formed at its front side with a vertical notch or recess 11. The latter divides the knife into two substantially semi-circular sections 12 which have their bottom edges 13 sharpened 55 and inclined rearwardly from their front to their rear ends, as shown more clearly in Fig.

2. At their front or lowermost ends are formed downwardly projecting pointed spurs 14 which are disposed on opposite sides of the notch or recess 11 and which are adapted 60 to readily puncture the top of a can and to start the cutting edges 13 of the knife sections 12 when the lever 2 is forced downwardly. The provision of the spurs or points 14 enable the knife to effectively cut 65 the top of the can when the lever is operated and the provision of the opening or recess 11 in the knife leaves a narrow connecting strip or neck in the can top between the two slits or cuts made by the knife sections 12 so that 70 the entire top of the can will not sag and be forced downwardly into the contents of the can, before the knife sections have finished their cutting stroke. This narrow strip or neck in the can top is severed by the front 75 portion of the knife as the rear ends or heel portion complete the cutting of the can; and the cut portion of the top of the can can then be bent back upon that portion which is not severed by the knife sections 12, as 80 will be readily understood. The knife may be connected to the lever 2 in any suitable manner but, as illustrated, it is fastened by bolts or rivets 15 to a lug 16 that projects from the lever. For the purpose of varying 85 the size of the knife to adapt it for cutting different sized cans, an adjusting member 17, preferably in the form of a bolt is arranged in apertures formed in the ends of the knife sections 12. A wing nut 18 upon the threaded end of the bolt permits said sections 12 to be drawn together to reduce the size of the cutter and when said nut is screwed outwardly upon the bolt the resiliency of the 90 knife sections will expand in the device, as 95 will be readily understood. While this is the preferred manner in which the improved cutting knife or blade is constructed and mounted, it will be understood that it may be otherwise shaped and constructed within 100 the scope of my invention.

Having thus described the invention what is claimed is:

1. A can opener comprising a base, a support, a lever fulcrumed thereon, a knife carried by the lever and consisting of a body portion of open circular form having a cutting edge inclined upwardly from its closed front end to its open rear end, said closed front end being formed with a recess to provide two substantially semi-circular sections, the front ends of the cutting edges of said

sections being formed with the depending pointed spurs 14, and an adjustable connection between the two semi-circular sections at the open rear end of the knife.

5 2. A can opener comprising a base, a support, a lever fulcrumed thereon, a knife carried by the lever and of open circular form, the separated ends of the knife being formed with transverse openings and an adjusting 10 screw or bolt arranged in said openings at

the ends of the knife, whereby the diameter of the cutting blade may be varied to fit cans of different sizes.

In testimony whereof I hereunto affix my signature in the presence of two witnesses. 15

ELMER W. BISHOP.
